CLOTHESLINE SUPPORT

Joseph C. Cordell, Mount Lebanon, Pa.

Application March 27, 1935, Serial No. 13,210

1 Claim. (Cl. 248—70)

My invention relates to improvements in clothes line supports.

One object of my invention is to provide a clothes line support that is so constructed that the distance the wires are suspended from the ceiling may be readily adjusted.

A second object of my invention is to provide a clothes line support that may be quickly installed in a basement or room and as easily removed therefrom.

Another object of my invention is to provide a clothes line support adapted to hold a plurality of wires and capable of adjustment, so the wires may be suspended parallel to the ceiling to which the supports are attached.

Briefly speaking my invention comprises providing two parallel rods, which are suspended from a ceiling by means of V shaped brackets. The brackets may be adjusted to change the vertical and horizontal position of the rods, thereby changing the position of the clothes lines that are suspended from said rods.

For a better understanding of my invention reference may be made to the accompanying drawing.

Figure 1 of which is a view, in perspective, of a clothes line support constructed in accordance with my invention.

Fig. 2 is a view, in perspective, of a strap which forms a part of one of the brackets illustrated in Fig. 1 of the drawing.

Fig. 3 is a view, in perspective, of one of the rigid members that forms part of a bracket illustrated by Fig. 1 of the drawing.

Fig. 4 is a view, in side elevation, of a wire and its means of attachment to the clothes line support by means of a bolt.

Fig. 5 is a view, in perspective, of a modified form of strap constituting a part of a bracket constructed in accordance with my invention.

Figs. 6 and 7 are views, in side and end elevation, respectively, of a plurality of brackets constructed in accordance with a modified form of my invention.

Fig. 8 is a cross sectional view of the bracket illustrated in Figs. 6 and 7 of the drawing taken along the line 8—8 of Fig. 7.

Fig. 9 is a view, partly in end elevation and partly in section, of a bracket constructed in accordance with my invention mounted on a steel I beam.

Referring to Fig. 1 of the drawing, a clothes line support 1 is attached to a plurality of rafters 2, which form a part of a horizontal support 3, which may be either a floor or ceiling.

Each of the supports 1 comprises a pair of brackets 4 which support a rod or bar 5. Two of these rods or bars 5 are so mounted by means of a plurality of brackets 4 as to be parallel to the horizontal support and to each other.

On the bars 5 are mounted a plurality of wires 6 by means of bolts 7 and 8. Each of the bolts 8 (Fig. 4) is provided with a threaded end 9 on which is rotatably mounted a washer 10 and a nut 11.

Each of the brackets 4 comprises a pair of rigid members 12 of L shaped cross section, one of which is illustrated in Fig. 3 of the drawing, and a metallic strap 13, which is separately disclosed in Fig. 2 of the drawing. The rigid members 12 and the metallic strap 13 are provided with a plurality of corresponding bolt holes 14 and 15, respectively, through which bolts 16 may be inserted.

Each of rigid members 12 is provided with a curved end portion 17 to permit a rolling contact with the surface on which it is mounted. In other words, as the angular relation of the rigid member 12 changes with respect to the rafter 2 a relatively flat portion of the rigid member 12 remains in contact with the rafter 2.

The clothes line support may be installed in any part of a building but is usually installed in the basement or attic. The method of installation is to fasten the rigid members 12 to the rafters 2 of the horizontal support 3. One of the straps 13 is fastened by the bolts 16 to the corresponding rigid members 12 to form the brackets 4.

The bar 5 is then slid through the looped portion 18 of each of the straps 13 that are in alignment. The bolts 16 nearest the bar 5 are tightened to hold the rod 5 securely in position.

A plurality of wires 6 are stretched between corresponding rods 5 by means of bolts 7 and 8. The wires 6 may be made as tight as desired by adjusting the nut 11 on the corresponding bolts 8.

A modified form of strap 21, which is illustrated in Fig. 5 of the drawing, has its end portions 22 pivotally fastened together by a bolt 23. This strap 21, while more expensive than straps 12, makes it easier to adjust the rod or bar 5 therein.

Referring to Figs. 6, 7, and 8, a different form of bracket 24 is illustrated supporting the pipe 5. This modified form of bracket comprises a rigid member 25 having a curved portion 26 at its one end and a second rigid member or metallic strap 27 having a hooked end 28 adapted to hold the pipe 5.

The metallic strap 27 has a U shaped block 29 welded thereto in which is positioned bolt 30, 55

which may be tightened to clamp the rigid members 25 and 27 together. This arrangement of the block 29 permits the rigid members 25 and 27 to be slid back and forth on each other to any desired position.

There are two brackets 24 at each end of the pipe 5. The brackets 24 are mounted in side by side relation on the pipe 5 and are independent of each other.

10 Referring to Fig. 9, a steel I beam 31 is illustrated as forming part of a horizontal support. A plate 32 is secured to the beam 31 by means of bolts 33. The rigid members 12 are then attached to the plate 32 by means of the bolts 34.

15 The rigid members 25 may also be tubular shaped, such as round or elliptical pipe, or U shaped, such as channels, and the adjustable members 27 may be also of corresponding cross section to fit said rigid members 25.

While I have shown my invention in a preferred form, it is apparent that minor modifications may be made in the arrangement of parts without departing from the spirit of my invention, I desire therefore to be limited only by the scope of the appended claim. 5

What I claim as my invention is:—

A pipe bracket comprising a strap with a looped end adapted to partially surround a pipe and an elongated rigid member having a curved end 10 portion adapted to have a tiltably adjustable engagement with a supporting surface and means for adjustably mounting said strap on said rigid member to vary the over all distance between the looped end of the strap and the curved end 15 portion of said rigid member.

JOSEPH C. CORDELL.
